Primary Examiner — Garth Rademaker*Assistant Examiner* — Melanie Pellegrini(74) *Attorney, Agent, or Firm* — Novak Druce Connolly Bove + Quigg LLP(57) **CLAIM**

I claim the ornamental design for a keshi pearl, as shown and described.

DESCRIPTION

FIG. 1 is a front perspective view of a first embodiment of a keshi pearl;

FIG. 2 is an alternate perspective view thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof;

FIG. 8 is a bottom plan view thereof; and

FIG. 9 is a front perspective view of a second embodiment of the keshi pearl;

FIG. 10 is an alternate perspective view thereof; and,

FIG. 11 is a front elevational view thereof, the remaining views of the second embodiment being the same as those of the first embodiment.

Broken lines are used to illustrate unclaimed portions of the keshi pearl; broken lines form no part of the claimed design.
